11 Claims. (Cl. 222—56)

This invention relates to a packaging machine. The invention has for an object to provide a novel and improved packaging machine having a material supply hopper from which the material is withdrawn to be packaged and in which provision is made for maintaining a substantially constant level of material in the supply hopper including control mechanism for terminating the delivery of material to the supply hopper when the latter is filled with a predetermined maximum amount of material and for terminating the operation of the packaging machine when the supply of material in the hopper falls below a predetermined minimum amount to the end that a substantially uniform head of material may be maintained in the supply hopper.

With this general object in view and such others as may hereinafter appear the invention consists in a packaging machine and in the various structures, arrangements, and combinations of parts hereinafter described and particularly defined in the claims at the end of this specification. In the drawings the invention has been illustrated as embodied in a packaging machine for filling cartons with weighed loads wherein Fig. 1 is a side elevation of such a machine, some of the parts being shown in cross section; Figs. 2 and 3 are detailed views of modified forms of material feeding apparatus to be referred to; Fig. 4 is a sectional side elevation illustrating a modification of the apparatus shown in Fig. 1; and Fig. 5 is a plan view in cross section of the supply hopper shown in Fig. 4.

In general, the present packaging machine embodies a supply hopper for storing a supply of the material to be packaged and from which the material flows downwardly through a conduit to be deposited in successive cartons conveyed beneath the same. The successive loads of material thus withdrawn may be formed in various known manners as by weighing or measuring. Provision is made for maintaining a substantially constant level of material in the material supply hopper in order to maintain the pressure head of the material therein substantially constant during the formation of successive loads being packaged. In this manner inaccuracies in the rate of flow of the material downwardly from the supply hopper through the conduit are avoided and more accurately formed loads are produced.

Referring now to the drawings which as above stated illustrate the different features of the invention as embodied in a packaging machine of the type wherein the loads are formed by weighing, the machine is provided with a material supply hopper 10 to which material is delivered by a conveyer 12 from any suitable source of supply, and from which the material is withdrawn by suitable material feeding mechanism, indicated generally at 14, to be introduced into a carton 16 resting upon one end of a scale beam 18.

For purposes of illustration, the invention has been shown as embodied in a commercial weighing machine of the type illustrated and described in the United States patent to Howard, No. 1,893,622, January 10, 1933, to which reference may be had for a more complete disclosure of the operation of such weighing machine. In general, the illustrated weighing machine may include an intermittently operated package moving mechanism including package pusher arms 20 mounted upon an endless chain 22 adapted to move a carton onto the scale pan 24 of the scale beam 18 during one period of operation, and control mechanism, indicated generally at 26, adapted to open and close the shutters 28, 30 of the material feeding mechanism 14 during another period of operation. In the automatic weighing machine the cartons are supplied to the machine upon an inlet conveyer 32 and successive cartons are transferred onto a platform 34 into the path of the pusher arms 20 by a transfer member 35. As fully described in the Howard patent above referred to, the machine is controlled to operate in successive cycles through connections actuated by the movement of the scale beam 18 whereby the shutters 28, 30 are closed and the package moving cycle of operation is initiated when the scale makes its weight. Thereafter when the package moving cycle has been completed, the shutters 28, 30 are again opened to permit the material to flow by gravity into a fresh carton delivered onto the scale. The material feeding mechanism 14 may be provided with the usual stirrers 36, 38 to facilitate the flow of the material therethrough. As herein shown, the machine may be driven by an electric motor 40 through its pulley 42 connected by a belt 44 to a drive pulley 46 on the machine. As will be hereinafter described, the electric motor 40 forms part of a circuit arranged to be opened to stop the machine when the weight of the material in the supply hopper falls below a predetermined minimum amount.

From the description thus far, it will be observed that the material is withdrawn from the supply hopper 10 by the feeding mechanism 14, the material falling by gravity through the bottom of the hopper as it is required by the feeding mechanism. In the embodiment of the invention, as illustrated in Fig. 1, the discharge end 48 of the hopper is loosely inserted into the top of the feeding mechanism, forming a telescopic connection, to permit the hopper to be raised or lowered with relation to the feeding mechanism in accordance with the weight of the material in the hopper as will be described.

As illustrated in Fig. 1, one form of mechanism for conveying the material from its source and delivering it to the supply hopper may comprise the conveyer 12 which may include a conduit 50 having an inlet 52 and an outlet 54 and through

which an endless conveying element 56 is arranged to run. The conveying element runs over an idler 58 at one end of the conduit and a driven sprocket 60 at the other end, such a conveyer being of a commercial form known in the trade and operating in accordance with the principles disclosed in the United States Redler Reissue Patent No. 18,445, to which reference is made. As herein shown, the conveyer is driven by an electric motor 62 having a pinion 64 in mesh with a gear 65 fast on the sprocket shaft 66. The electric motor 62 forms part of a circuit arranged to be opened to stop the conveyer when the weight of the material in the hopper exceeds a predetermined maximum, as will be hereinafter described. For the purpose of the present invention, it is sufficient to state that the conveying element 56 when moved through the conveyer casing operates to convey the material in a continuous stream from the inlet 52 to be discharged through the outlet 54.

As herein illustrated, see Fig. 1, the material supply hopper 10 may be supported upon compression springs 78, coiled about studs 72 extending from a platform 74, the latter being supported by rods 76 depending from the floor above. The platform 74 is provided with an opening 78 through which the lower portion of the hopper extends. The studs 72 are slidingly fitted through bearings 80 provided in a flanged portion 82 of the hopper 10. Thus, the hopper is free to move vertically under the influence of the weight of the material in the hopper.

Provision is made for controlling the operation of the supply conveyer 12 and the operation of the weighing machine in accordance with the weight of the material in the supply hopper 10 as indicated by the vertical movement of the hopper. As herein shown, a circuit 84 to the conveyer motor 62 includes a switch 86 having a stationary contact 88 and a movable contact 90, the latter being pivotally mounted in the switch supporting bracket 82 attached to the stationary platform 74. The switch is normally held in its closed position as illustrated in Fig. 1, by a common spring 94 extended between the switch arm 96 and a similar switch arm 98 forming part of a similar switch 100 included in a circuit 102 leading to the machine motor 48. A switch arm engaging stud 104 vertically and adjustably mounted in a bracket 106 is secured to the side of the hopper 10, and normally, when the hopper is filled with the normal amount of material, the stud 104 is disposed between the two arms 88, 98 without engaging either. In operation, if the hopper 10 is filled above a predetermined height, the additional weight of the material will cause the hopper to descend. The stud 104 will then engage the arm 98 and open the circuit 84 at the contacts 88, 90 thereby stopping the conveyer motor 62 and consequently stopping the delivery of the material to the hopper. During the operation of the machine, continued withdrawals of material from the hopper will cause the hopper to rise under the influence of the springs 78 and the contacts 88, 90 will be reestablished to again feed material to the hopper.

In the event that the supply of material at its source is depleted, or, if for some other reason, the conveyer 12 fails to replenish the material withdrawn from the hopper, continued withdrawal of material will cause the hopper to become abnormally light, and when this occurs, the springs 78 will raise the hopper and the stud 104 will engage the arm 98 and open the circuit

102 at contacts 108, 110, thereby stopping the machine motor 48. When the required amount of material has been delivered to the hopper by the conveyer 12, the contacts 108, 110 will be re-established to again start the weighing machine. Thus, a substantially constant level of material is maintained in the hopper 10 through the use of the limiting switches 86, 100 operated by vertical movement of the hopper effected by the relative weight of the material therein. The usual cut-out switches 112, 114 may be provided in the circuits 84, 102 respectively, in order to permit operation of the conveyer 12 or the weighing machine without going through the limiting switches, when such operation is necessary.

Referring now to Figs. 2 and 3, modified forms of the mechanism for delivering material to the supply hopper 10 are herein illustrated. In Fig. 2, a vibratory feeder 116 is employed. Material is delivered through a funnel 118 from a source of supply onto the vibratory feeder which is operated through a vibratory motor 120 to deliver the material into the hopper 10. The vibratory motor 120 is provided with leads 122, 124 which may be included in the circuit 84 in place of the motor 62 in order to start and stop the vibration of the vibratory motor 120 in accordance with the amount of material in the hopper 10, as above described, whereby the feed of the material into the hopper may be thus controlled.

Another modification of the mechanism for delivering material to the supply hopper 10, as illustrated in Fig. 3, may comprise a funnel 126 through which the material may flow by gravity from the source of supply into the hopper 10. As herein shown, the funnel 126 is provided with a gate or shutter 128 which may be operated by a solenoid 130 having leads 132, 134 which may be connected in the circuit 84, as above described, to control the feed of the material in accordance with the amount of material in the hopper.

Referring now to Figs. 4 and 5, a modified form of the mechanism for controlling the amount of material in the supply hopper may comprise a mechanism for maintaining a substantially constant level of the material therein. As herein shown, such mechanism may include a fixed supply hopper 140 having light sensitive cells 142, 144 cooperating with light sources 146, 148 respectively, mounted at different levels in the hopper. The light sensitive elements are enclosed in casings 150, 152 secured to the outside of the hopper and are provided with condensing lenses 154, 156 secured to the inner wall of the hopper for concentrating the rays of light from the light sources onto the photo-electric cells. The light sources are likewise enclosed in suitable casings 158, 160 and are protected from the material in the hopper by glass panels 162, 164.

The hopper is provided with a cover 166 and material may be delivered through an offset opening 167 therein, as shown in Fig. 5. The material may be delivered by a conveyer 168 which may be driven by a motor 170, the latter being diagrammatically shown in the wiring circuit in Fig. 4. Power is supplied to the motor through the main leads 172, 174 through a solenoid operated switch 176. When the material in the hopper rises above the level of the upper light sensitive cells 142 it will intercept the light ray from the source 146 and as a result, a relay mechanism which may be of any well-known type indicated at 178 becomes operative to actuate the solenoid 180 to open the circuit to the conveyer motor 170 at the switch 176 to thereby terminate

the delivery of material to the hopper. Continued withdrawals of material from the hopper will lower the level therein to again expose the photo-electric cell 142 to the ray of light 146 whereupon the switch 175 will again be closed to start the conveyor 188.

The photo-electric cell 142 is connected to the relay 178 by the leads 182, 184. Leads 185, 186 connect the main leads to the relay. The solenoid 180 is connected to the relay by leads 187, 189. The source of light 146 is supplied with current through the leads 190, 192. In operation, the relay 178 is adapted to close the circuit within the relay to operate the solenoid 180 when the light ray to the photo-electric cell 142 is cut off. Normally, the photo-electric cell will not operate the relay when it is receiving a sufficient amount of light. As above described, the incoming supply of material to the hopper is disposed in an offset position so that the incoming stream of material will not operate to cut off the light ray.

On the other hand, should the material in the hopper become depleted below the level of the lower light sensitive cell 144, to expose the cell to the ray of light from the source 148, a relay mechanism 195 will become operative to actuate a solenoid 196 to open the circuit to the machine motor 198 at the switch 200. As herein shown, power is supplied to the motor 198 from the main leads 172, 174 and through leads 202, 204. The connections to the relay 195 include the leads 206, 208 from the main leads, the leads 210, 212, to the photo-electric cell 144 and the leads 214, 216 to the solenoid 196. The light source 148 is connected to the power supply through leads 218, 220. Normally, when the light source is cut off by the material in the hopper, the switch 200 will remain closed to drive the machine. However, when the photo-electric cell 144 is exposed to the light the relay 195 will operate to energize the solenoid 196 to open the circuit at the switch 200. Thus, the level of the material in the hopper is maintained at a substantially constant level, within the limits of the different levels of the light sensitive cells 142, 144.

From the above description, it will be observed that provision is made in the present weighing machine for assuring a substantially constant head of material in the supply hopper whereby the gravitational flow from the hopper is maintained substantially uniform thus effecting a substantially constant impact force upon the scale beam to the end that errors in weights which have heretofore accompanied variations in the flow of the material being weighed, may be reduced to a minimum.

This application is a division of my co-pending application, Serial No. 327,755, filed April 4, 1940.

Having thus described the invention what is claimed is:

1. A packaging machine having in combination, material feeding means, a supply hopper to which material is fed by said feeding means, a conduit leading downwardly from the supply hopper and through which material may fall by gravity, means for forming successive loads of the material withdrawn from the supply hopper through said conduit, and control means for maintaining a substantially constant amount of material in said supply hopper whereby to effect a substantially uniform gravitational flow of material from said feeding means, said control means including means for terminating the delivery of material to the supply hopper when the latter becomes filled in excess of a predetermined

amount and means for terminating the operation of the load forming means when the hopper becomes depleted below a predetermined and less amount of material.

5 2. A packaging machine having in combination, material feeding means, a supply hopper to which material is fed by said feeding means, a conduit leading downwardly from the supply hopper and through which material may fall by gravity, means for forming successive loads of the material withdrawn from the supply hopper through said conduit, and control means for maintaining a substantially constant amount of material in said supply hopper whereby to effect a substantially uniform gravitational flow from said feeding means, said control means including means for supporting said hopper adapted to permit the latter to move vertically under the influence of the weight of the material in the hopper, and means operatively connected to said hopper for terminating the delivery of material thereto when the weight of the material in the hopper exceeds a predetermined amount and for initiating such delivery when said weight falls below said amount, and means for terminating the operation of the load forming means when said weight falls below a predetermined but substantially less amount.

3. A packaging machine having in combination, material feeding means, a supply hopper to which material is fed by said feeding means, a conduit leading downwardly from the supply hopper and through which material may fall by gravity, means for forming successive loads of the material withdrawn from the supply hopper through said conduit, and control means for maintaining a substantially constant amount of material in said supply hopper whereby to effect a substantially uniform gravitational flow of material from said feeding means, said control means including means for supporting said hopper adapted to permit the latter to move vertically under the influence of the weight of the material in the hopper, a pair of limiting switches 40 adapted to be operated by the vertical movement of said hopper for terminating the delivery of material thereto when the weight of the material therein exceeds a predetermined maximum and for terminating the operation of the load forming means when said weight falls below a predetermined minimum.

4. A packaging machine having in combination, material feeding means, a supply hopper to which material is fed by said feeding means, a conduit leading downwardly from the supply hopper and through which material may fall by gravity, means for forming successive loads of the material withdrawn from the supply hopper through said conduit, and control means for maintaining a substantially constant level of material in said supply hopper whereby to effect a substantially uniform gravitational flow of material from said feeding means, said control means including means for terminating the delivery of material thereto when the level thereof exceeds a predetermined maximum height and means for terminating the operation of the load forming means when said level is reduced below a predetermined minimum height.

5. A packaging machine having in combination, material feeding means, a supply hopper to which material is fed by said feeding means, a conduit leading downwardly from the supply hopper and through which material may fall by gravity, means for forming successive loads of

the material withdrawn from the supply hopper through said conduit, and control means for maintaining a substantially constant level of material in said supply hopper whereby to effect a substantially uniform gravitational flow of material from said feeding means, said control means including photo-electric means responsive to the changes in the level of said material for terminating the delivery of material to said hopper when the level exceeds a predetermined maximum height and for terminating the operation of the load forming means when said level is reduced below a predetermined minimum height.

6. A packaging machine having in combination, material feeding means, a supply hopper to which material is fed by said feeding means, a conduit leading downwardly from the supply hopper and through which material may fall by gravity, means for forming successive loads of the material withdrawn from the supply hopper through said conduit, and control means for maintaining a substantially constant level of material in said supply hopper whereby to effect a substantially uniform gravitational flow of material from said feeding means, said control means including means for terminating the delivery of material thereto when the level thereof exceeds a predetermined maximum height, and for causing said delivery to be resumed when the material level falls below said maximum height, and means for terminating the operation of the load forming means when the level falls below a different and lower height.

7. A packaging machine having in combination, material feeding means, a supply hopper to which material is fed by said feeding means, a conduit leading downwardly from the supply hopper, means for forming successive loads of the material withdrawn from the supply hopper through said conduit, and control means for maintaining a substantially constant level of material in said supply hopper whereby to effect a substantially uniform gravitational flow of material from said feeding means, said control means including means for terminating the delivery of material thereto when the level thereof exceeds a predetermined maximum height, and for causing said delivery to be resumed when the material level falls below said maximum height, and means for terminating the operation of the load forming means when the level falls below a different and lower height.

8. A packaging machine having in combination material feeding means for feeding material by gravity, a supply hopper located above and in direct communication with said feeding means and from which material is withdrawn, the rate at which material is fed by said feeding means being at least to some extent related to the head of material in the supply hopper, means for delivering material to said supply hopper, and control means for maintaining a substantially constant amount of material in said supply hopper whereby to effect a substantially uniform gravitational flow from said feeding means, said control means including means for supporting said hopper adapted to permit the latter to move vertically under the influence of the weight of the material in the hopper, means operatively connected to said hopper for terminating the delivery of material thereto when the weight of the material in the hopper exceeds a predetermined amount and for initiating such delivery

when said weight falls below said amount, and means for terminating operation of said feeding means when said weight falls below a predetermined but substantially less amount.

9. A packaging machine having in combination material feeding means for feeding material by gravity, a supply hopper located above and in direct communication with said feeding means and from which material is withdrawn, the rate at which material is fed by said feeding means being at least to some extent related to the head of material in the supply hopper, means for delivering material to said supply hopper, and control means for maintaining a substantially constant amount of material in said supply hopper whereby to effect a substantially uniform gravitational flow of material from said feeding means, said control means including means for supporting said hopper adapted to permit the latter to move vertically under the influence of the weight of the material in the hopper, a pair of limiting switches adapted to be operated by the vertical movement of said hopper for terminating the delivery of material thereto when the weight of the material therein exceeds a predetermined maximum and for terminating the operation of said feeding means when said weight falls below a predetermined minimum.

10. A packaging machine having in combination material feeding means, including a supply hopper provided with a conduit extended downwardly therefrom and through which material may flow by gravity from the hopper, means for delivering material to the supply hopper, and control means for maintaining a substantially constant amount of material in said supply hopper whereby to effect a substantially uniform gravitational flow from said feeding means, said control means including means for supporting said hopper adapted to permit the latter to move vertically under the influence of the weight of the material in the hopper, means operatively connected to said hopper for terminating the delivery of material thereto when the weight of the material in the hopper exceeds a predetermined amount and for initiating such delivery when said weight falls below said amount, and means for terminating operation of said feeding means when said weight falls below a predetermined but substantially less amount.

11. A packaging machine having in combination material feeding means including a supply hopper provided with a conduit extended downwardly therefrom and through which material may flow by gravity from the hopper, means for delivering material to said supply hopper, and control means for maintaining a substantially constant amount of material in said supply hopper whereby to effect a substantially uniform gravitational flow of material from said feeding means, said control means including means for supporting said hopper adapted to permit the latter to move vertically under the influence of the weight of the material in the hopper, a pair of limiting switches adapted to be operated by the vertical movement of said hopper for terminating the delivery of material thereto when the weight of the material therein exceeds a predetermined maximum and for terminating the operation of said feeding means when said weight falls below a predetermined minimum.

ARTHUR W. LINDHOLM.
